(57) **CLAIM**

The ornamental design for folding delta table, as shown and described.

DESCRIPTION

FIG. 1 is a top perspective view of the folding delta table showing my new design;

FIG. 2 is a bottom perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front side elevation view thereof;

FIG. 8 is a back side elevation view thereof;

FIG. 9 is a bottom perspective view thereof in a partially folded configuration; and,

FIG. 10 is a perspective view thereof in a partially folded configuration.

The broken lines show portions of the folding delta table that form no part of the claimed design.

1 Claim, 8 Drawing Sheets
